[57] CLAIM

The ornamental design for a fireplace screen, as shown
and described.

DESCRIPTION

FIG. 1 is a front elevational view of a fireplace screen
showing my new design;

FIG. 2 is a top plan view thereof;

FIG. 3 is a left side elevational view thereof;

FIG. 4 is a right side elevational view thereof;

FIG. 5 a front elevational view shown with the doors
opened;

FIG. 6 is a front elevational view of a second embodiment
of a fireplace screen, wherein the only difference
resides in the placement of the circular apertures.

The broken line disclosure of a fireplace in FIG. 1 is for
illustrative purposes only and forms no part of the
claimed design.
